US00D336712S

United States Patent [19]
Ledingham

[11] **Patent Number:** Des. 336,712
[45] **Date of Patent:** ** Jun. 22, 1993

[54] **FLEXIBLE PLASTIC RETURN WAY FOR CONVEYOR CHAINS**

[75] Inventor: **Stuart J. Ledingham**, Coto de Caza, Calif.

[73] Assignee: **Valu Engineering, Inc.**, Irvine, Calif.

[**] Term: **14 Years**

[21] Appl. No.: **611,362**

[22] Filed: **Nov. 9, 1990**

[52] U.S. Cl. **D34/29**

[58] Field of Search D34/29; 198/841, 750; D25/119, 136; 52/290, 303

[57] **CLAIM**

The ornamental design for a flexible plastic return way for conveyor chains, shown and described.

DESCRIPTION

FIG. 1 is a partial isometric view of a flexible plastic return way for conveyor chains, embodying my new design;

FIG. 2 is an end view of either end thereof;

FIG. 3 is a side view of either side thereof; and,

FIG. 4 is a bottom view thereof.

The claimed article is partially shown to indicate indeterminate length.

FIG. 1.

FIG. 2.

FIG. 3.

FIG. 4.
